METHOD AND APPARATUS FOR COOLING
METAL MOLDS

Henry E. McWane, Lynchburg, Va.

Application January 3, 1942, Serial No. 425,569

6 Claims. (Cl. 22—177)

The present invention relates to casting, and more particularly it has reference to a method and apparatus for cooling metal molds so that the danger of the cooling media entering the casting cavity is minimized.

Of course, means have heretofore been provided for cooling permanent metal molds, but, to the best of my knowledge, the cooling media or water has always been admitted into the water jacket under pressure. While this type of cooling is generally satisfactory, it does present one problem which has always caused difficulty in the industry. As is well known, metal molds often develop small cracks or fissures which extend into the casting cavity. Consequently, when the water in the jacket is under pressure, there is a real danger that the water will be admitted into the casting cavity in the event the crack is of sufficient size, thereby causing an explosion not only damaging the mold but also proving hazardous to the foundrymen.

An object of the present invention is to provide a method and apparatus for cooling permanent metal molds wherein the cooling media is circulated throughout the water jacket under negative pressure.

Another object of the present invention is to provide a novel cooling system for permanent molds wherein the cooling media is not circulated in the jacket at elevated pressures.

And a further object of the present invention is to provide means for supplying cooling media to a water jacket at such pressures as will prevent the water or cooling media entering the casting cavity.

To accomplish the above and other important objects, the invention in general comprises connecting the water jacket with a source of cooling media in such a manner that the water is drawn from the source of supply into the water jacket and thence back to the source of supply.

More specifically, a pump is provided on the suction side of the mold whereby the water circulating through the water jacket will be kept at a negative pressure, thus eliminating the danger of the water entering the mold cavity through any small cracks or fissures which may be present in the mold body.

In the drawings in which like numerals indicate the same or similar parts:

Figure 1 is a diagrammatic representation of a source of cooling media and a casting machine illustrating the connections between the source of supply and the casting machine for circu-

lating the cooling media in the water jackets of the mold parts.

Figure 2 is a transverse sectional view taken along the line 2—2 of Figure 1 looking in the direction of the arrows.

Figure 3 is a transverse sectional view taken along the line 3—3 of Figure 1 looking in the direction of the arrows.

In Figure 1 there is shown a supply tank 1 for water or some other suitable cooling medium. The tank 1 is mounted above the floor of the foundry upon a support 2 and is in communication with water jackets 3 and 4 of fixed and movable mold parts 5 and 6, respectively, by means of a system of pipes or conduits designated generally 7. The fixed and movable mold parts are supported upon a casting frame indicated 8, and the construction and operation of the casting frame and its associated parts are shown and described in my copending application Serial No. 413,214, filed October 1, 1941, now Patent 2,313,253, dated March 9, 1943.

As best shown in Figure 1, an inlet pipe 9 has interposed therein a valve 10 for controlling the flow of water into the tank 1 from a watermain (not shown). An outlet 11 located adjacent to the bottom wall of the tank 1 is provided with a control valve 12 and conduit 13 is suitably coupled to the valve 12. The conduit 13 extends below the surface of the foundry floor or the like, and a main inlet conduit 14 is attached to the lower end of the conduit 13 as shown at 15. Secured to the main conduit 14 by a T-connection 16 is a lateral conduit 17. Coupled to the pipe 17 is a vertical conduit 18 which terminates above the floor of the foundry adjacent to the frame 8. A flexible conduit 19 is attached to the upper end of the conduit 18, as shown at 20, and the opposite end thereof is in communication with the water jacket 3 of the fixed mold part 5. A second flexible conduit 21 extends from the water jacket 3 to the upper end of a vertical conduit 22 which is secured by a T-connection 23 to a lateral pipe 24. The pipe 24 is conveniently coupled at 25 to a main return pipe 26 which is parallel to the pipe 14. A vertical section of pipe 27 is coupled to the end of the main return conduit or pipe 26 and the upper end of the conduit 27 is suitably connected to a suction pump 28 mounted on the support 2. The pump 28 is adapted to be driven by an electric motor 29 through a connection 30. Conduit 31 is secured at its lower end to the pressure side of the pump 28, and attached to the upper end thereof as shown at 32 is a spray pipe

33 that is disposed within the tank 1 adjacent to the upper end thereof. An overflow aperture 34 provided adjacent to the upper end of the tank has connected thereto an overflow pipe 35 which is attached by a T-connection 36 to a conduit 37 that leads to a suitable drain which is not shown. The pipe 37 has provided therein a control valve 38 which is connected to the conduit 14 in any desirable manner. A similar control valve 39 is also connected to the pipe 14 and to the pipe or return conduit 26. The purpose of these valves will later be more fully described.

To cool the movable mold part 6 I provide an arrangement which is similar to that for cooling the fixed mold part and the corresponding elements bear the same numerals with the exception that they are primed.

It should be mentioned that my invention is generally employed in connection with a series of casting frames 8, and the mold parts of each frame are connected to the tank 1 in the same manner as the frame 8 just described.

While the operation of my system is believed to be readily apparent from the above description, it may be briefly summarized as follows. When the requisite amount of cooling medium, sufficient only to completely fill the water jackets of all the molds employed in the above-mentioned series has been admitted into the tank 1 through the inlet conduit 9, the valve 10 is manipulated to arrest the flow of the water. The suction pump 28, of course, is driven through the motor 29 and water is drawn from the tank 1 through the conduit 13 past the open valve 12 into the main pipe or conduit 14. Of course, the control valves 38 and 39, provided in the conduit 37 which leads to the drain, are closed to prevent the water from by-passing into the drain. The water is drawn from the main conduit 14 through the lateral conduits 17 and 17' into the vertical pipes 18 and 18' through flexible conduits 19 and 19' into the water jackets 3 and 4 to cool the mold parts 5 and 6, respectively. The water circulates through the jackets and is drawn out through the flexible connections 21 and 21' into the vertical pipes 22 and 22' and into the lateral conduits 24 and 24'. From the lateral conduits 24 and 24' the water enters the main return conduit 26 and is drawn into the pump 28 and is discharged through the vertical pipe 31 and into the spray pipe 33. The water leaving the spray pipe 33, of course, is cooled by condensation.

In the event it is desired to drain the water from the system, the valves 38 and 39 are actuated to permit the conduits 14 and 26 to communicate with the conduit 37 and the operation thereof is thought to be readily apparent.

It should be mentioned that when the whole system is filled with the cooling medium, the column of liquid in the tank 1 is balanced by that in the water jackets of the molds and consequently the water in the water jackets will not be under pressure and when the suction pump 28 is operating the pressure in the jackets will be reduced below atmospheric. This is particularly important in that there is no danger of the water entering the casting cavity through any cracks or the like which may be present in the mold parts. Hence the danger of an explosion occurring within the casting cavity is reduced materially.

The apparatus by which I control the cooling of the metal mold parts is simple in construction and in operation and can be manufactured at a relatively low cost. The inlet and outlet conduits leading from the tank to the casting machine are

below the floor level of the foundry and the advantages of this feature are thought to be clear. Furthermore, in the event of injury to any of the equipment, it is possible to repair or replace the equipment in a minimum of time.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. A method of cooling water jacketed metal molds comprising introducing a cooling liquid from an open reservoir thereof into the water jacket wherein the hydrostatic head of the liquid in the jacket is equal substantially to the hydrostatic head of liquid in the reservoir, and withdrawing liquid from the jacket by suction to reduce the pressure in the jacket to a pressure below atmospheric.

2. A method of cooling water jacketed metal molds comprising introducing a cooling liquid from an open reservoir thereof into the water jacket wherein the hydrostatic head of the liquid in the jacket is equal substantially to the hydrostatic head of liquid in the reservoir, withdrawing liquid from the jacket by suction to reduce the pressure in the jacket to a pressure below atmospheric, and returning the withdrawn liquid to the said reservoir.

3. A method of cooling water jacketed metal molds comprising introducing a cooling liquid from an open reservoir thereof into the water jacket wherein the hydrostatic head of the liquid in the jacket is equal substantially to the hydrostatic head of liquid in the reservoir, withdrawing liquid from the jacket by suction to reduce the pressure in the jacket to a pressure below atmospheric, cooling the withdrawn liquid, and returning the withdrawn liquid to the said reservoir.

4. A method of cooling water jacketed metal molds comprising introducing a cooling liquid from an open reservoir thereof into the water jacket wherein the hydrostatic head of the liquid in the jacket is equal substantially to the hydrostatic head of liquid in the reservoir, withdrawing liquid from the jacket by suction to reduce the pressure in the jacket to a pressure below atmospheric, and spraying the withdrawn liquid into said reservoir in contact with the air to effect a cooling of the returned liquid.

5. In an apparatus for cooling metal molds having a water jacket, a tank containing a cooling liquid, conduit means connecting the tank with the water jacket for supplying liquid from the tank to said jacket, an overflow pipe communicating with the tank for controlling the amount of liquid therein whereby the hydrostatic head of the liquid in the jacket when filled balances substantially the hydrostatic head of liquid in the tank, additional conduit means connecting the jacket with the tank, and a suction pump associated with the last named conduit means for withdrawing liquid from the jacket and discharging it into the tank to establish thereby a circulation of liquid in the jacket at a pressure below atmospheric.

6. In an apparatus for cooling metal molds having a water jacket, a tank containing a cooling liquid, conduit means connecting the tank with

the water jacket for supplying liquid from the tank to said jacket, an overflow pipe communicating with the tank for controlling the amount of liquid therein whereby the hydrostatic head of the liquid in the jacket when filled balances substantially the hydrostatic head of liquid in the tank, a suction pump, a conduit connecting the jacket with the input side of said pump, a second conduit having a connection with the discharge

5 side of the pump and communicating with the tank in a region above the liquid level therein, said pump adapted to withdraw liquid from the jacket and discharge it to the tank to establish thereby a circulation of liquid in the jacket at a pressure below atmospheric, and a plurality of orifices in the last named conduit for discharging the liquid into the tank in the form of a spray.

HENRY E. McWANE.
